UNITED STATES PATENT OFFICE

JOHN ASTROM, OF FORT WAYNE, INDIANA

CARBURETOR

Application filed May 31, 1924. Serial No. 717,070.

This invention relates to carbureting apparatus for oil burning systems.

In many oil burning systems on the market today, particularly in those used for domestic heating, there is an ever present possibility and danger of flooding the burner, the furnace or the premises with fuel oil, which is fed either under a gravity head or under pressure, and the various devices employed 10 for safety do not furnish positive protection.

Another undesirable feature of most such systems is that a certain quantity of fuel oil must be stored inside the house either in an elevated gravity tank or in a pressure 15 tank, and the fire hazard of such storage is obvious.

A further common defect in such systems is that the oil is not thoroughly and uniformly mixed with the air necessary for combustion before reaching the burner or furnace, resulting in incomplete combustion, formation of soot and uneconomical operation. 20

Still another feature of many oil burning systems is that the quantity of oil mixed with 25 the air or the richness of the mixture is regulated by admitting the oil through a jet or adjustable needle valve, the adjustment being very delicate and the small valve liable to clog up by traces of dirt or sediment.

30 This invention is designed to overcome the above noted defects and objects of such invention are to provide an improved oil burning system particularly adapted for domestic heating in which the fuel oil under no circumstances can flood the burner, the furnace or the premises, which requires no safety devices for the prevention of such possible flooding, which requires no oil storage inside 35 the building, in which the air and oil are thoroughly and uniformly mixed before reaching the burner or furnace to insure satisfactory, economical combustion, and in which the proper richness of mixture of oil 40 with air is obtained without regulating the quantity of oil admitted.

An embodiment of the invention is shown in the accompanying drawings, in which:

Figure 1 is a side elevation.

50 Figure 2 is an end elevation, partly in sec-

tion, of a convenient self-contained arrangement.

A fully enclosed atomizing chamber 1 provided with supporting lugs 2 is suspended on columns 3 and tie rods 4 from a base 5. 55 The columns 3 are extended above the atomizing chamber 1 and carry a bed plate 6 upon which are mounted an electric motor 7 the extended shaft of which by means of couplings 8 drives a blower 9 at one end and an oil pump 10 at the opposite end, the said blower and oil pump being supported and aligned upon said bed plate. The air for combustion is delivered by the blower 9 through the pipe 11 which enters the atomizing chamber 1 near its bottom. The air leaves the atomizing chamber at its top through the pipe 12 which conducts it to the burner 13 or other suitably arranged place of combustion. The burner 13, if employed, 60 has a pilot light in the form of a Bunsen burner 14 receiving gas through a pipe 15 whereby it is kept heated and whereby the combustible mixture of fuel oil and air is ignited upon reaching the burner, as is common 65 practice. 70

The oil pump 10 draws fuel oil through pipe 16 from a storage tank 17 located below the level of the floor line and atomizing chamber 1 and preferably buried in the ground. 75 The pump forces the oil through pipe 18 which enters the atomizing chamber at its upper part into the atomizer 19, here shown located in the center of chamber 1, where the oil escapes into the chamber in the form of a 80 very fine mist or fog. 85

It will be seen particularly from Figure 2 of the drawings that a downwardly directed spray is projected and forms a fine mist, thereby creating a mist-zone extending downwardly from the nozzle to the bottom of the tank and laterally to the sides of the tank in a cone-like formation. 90

The air pipes 11 and 12 are connected by means of a by-pass pipe 20 in which is located 95 a stop valve 21, preferably in the shape of a balanced butterfly valve as shown, which is operated by means of a lever arm 22. In the pipe 11, and between the by-pass pipe 20, and the atomizing chamber 1, a similar valve 100

23 is located, operated by means of lever arm 24. The operation of these valves is made simultaneous by connecting the lever arms 22 and 24 by a link 25 in such a manner that 5 when valve 21 is opened valve 23 is closed and vice versa.

A drain pipe 26 connects the bottom of atomizing chamber 1 with the oil storage tank 17. The pipe 26 is of ample size to drain all 10 the oil pumped by oil pump 10 from the atomizing tank back to the storage tank by gravity.

The operation of the oil burning system described is as follows:—

15 Upon starting up the motor 7 the blower 9 forces a strong current of air through pipe 11 into atomizing chamber 1 where it passes through and is mixed with the oil delivered by the oil pump 10 and atomized by the 20 atomizer 19. The mixture of air and oil now passes on through pipe 12 into the burner 13 where it is ignited and maintains combustion as long as the motor is in operation. Any oil not used by the burner or not brought 25 into a sufficiently fine state of atomization to be carried along with the air collects in the bottom part of the atomizing chamber and drains back into the storage tank 17 by gravity. When the valve 21 is open and the 30 valve 23 closed all the air delivered by blower 9 passes through atomizing chamber 1 and a very rich mixture enters the burner. When valve 23 is closed and valve 21 is open all the air will pass through by-pass pipe 20 35 directly to the burner where no combustion can take place for lack of oil. Between these two extreme positions of the valves lies a position which will produce the proper richness of mixture for complete and economical 40 combustion which can easily be found by watching the flame. Upon stopping the motor the supply of air as well as oil ceases and the atomizing chamber completely drains into the storage tank while the fire 45 goes out.

It is thus evident that in the oil burning system described all danger of flooding the burner or furnace with fuel oil is avoided without the use of any safety device for such 50 purpose, that there is no storage of oil inside the building, that the air and oil are thoroughly mixed in the atomizing chamber before reaching the burner and that the richness of the mixture of oil with the air is 55 regulated by forcing more or less of the air through the atomizing chamber without regulating the amount of oil admitted through the atomizer into the atomizing chamber.

60 While the arrangement of parts shown is a convenient one it lies within the scope of the invention to arrange the several units in different relative positions, to modify the size and shape of the atomizing chamber, to 65 use screens or baffle plates within said cham-

ber, and to make use of more than one atomizer of any suitable design, pointing the nozzles in any direction found most advantageous to secure the best results depending upon the consistency of the fuel oil used and 70 other variable circumstances.

Although the invention has been described in considerable detail, it is to be understood that the invention may be variously embodied and is, therefore, to be limited only as 75 claimed.

I claim:

1. The combination of a fuel supply tank, a closed atomizing tank located at a higher level than said supply tank, said atomizing tank having an open unobstructed interior, a return pipe leading from the lower end of said atomizing tank to said fuel tank, an air pipe leading into the lower portion of said atomizing tank, externally located means for forcing a blast of air through said pipe into said tank, an outlet pipe leading from the upper end of said atomizing tank, a fuel spray nozzle located within said atomizing tank adjacent its upper end and directed downwardly for projecting a spray of fuel downwardly in a fine mist to thereby create a mist-zone extending downwardly from said nozzle to the bottom of said tank and laterally to the sides of said tank in a cone-like formation, whereby the air is forced to pass in an upward direction through the downwardly passing mist of fuel, means for drawing fuel from said fuel tank and forcing such fuel under pressure through said nozzle, whereby the outwardly passing air entrains a mist of fuel with the fuel in a finely divided state. 95

2. The combination of a fuel supply tank, a closed atomizing tank located at a higher level than the supply tank and having a return pipe leading from the lower end of said atomizing tank, externally located means for forcing air into the lower portion of said atomizing tank, said atomizing tank having a centrally located outlet at its upper end, a fuel supply pipe leading upwardly from the supply tank and extending through the side wall of the atomizing tank, a fuel spray nozzle attached to the supply tank and arranged in said atomizing tank adjacent its upper end for directing a spray of fuel downwardly to create a mist-zone of cone-like formation contacting with the side walls of said atomizing tank and substantially filling the lower portion of said tank, and means for drawing fuel from said fuel tank and forcing said fuel under pressure through said nozzle whereby the air entering the lower portion of said atomizing tank is forced to pass through the mist-zone on its way to said outlet. 110

In testimony that I claim the foregoing I have hereunto set my hand at Fort Wayne, in the county of Allen and State of Indiana.

JOHN ASTROM. 132
